COMBINED SOFA BED AND TABLE UNIT

Louis Elliott Frey, Los Angeles, Calif.

Application March 28, 1957, Serial No. 45,475

Term of patent 14 years

(Cl. D5—4)

Fig. 1 is a perspective view showing a combined sofa bed and table unit embodying my new design, with the beds in closed position;

Fig. 2 is a perspective view of the same, with the beds in open position.

I claim:

The ornamental design for combined sofa bed and table unit, substantially as shown.
